United States Patent Office.

HARRY HUBBARD EVARTS, OF CHICAGO, ILLINOIS.

Design No. 4,031, dated May 17, 1870.

DESIGN FOR A DOVETAIL.

The Schedule referred to in these Letters Patent and making part of the same.

To all whom it may concern:

Be it known that I, HARRY HUBBARD EVARTS, of Chicago, in the county of Cook and State of Illinois, have invented or produced a new and original Design for Dovetails for cabinet and other work, of which the following is a specification.

This design consists in making the corners of the ends of the dovetails and pins round, as hereinafter described.

Figure 1 is a view, showing the dovetails united.

Figure 2, a view, showing them separated.

A A represent the dovetails, and

B B, the pins.

The corners of each are rounded, as shown at a a.

This gives a much more pleasing and ornamental appearance to the work than where sharp corners are

used, as it relieves the eye of the monotony and irregularity presented. Those shown are of the kind that do not protrude or rise above the general level.

The following elements of utility are involved:

Greater strength is produced, there is less splintering, and the corners are not so easily broken and disfigured.

What I claim is the design for dovetails, as herein described and represented.

In witness whereof I have hereunto signed my name in the presence of two subscribing witnesses.

HARRY HUBBARD EVARTS.

Witnesses:

J. R. DRAKE,

ALBERT HAIGHT.
